CLAIM

The ornamental design for a lidar, as shown and described.

DESCRIPTION

FIG. 1 is a front view of a lidar showing my new design.

FIG. 2 is a back view thereof.

FIG. 3 is a left view thereof.

FIG. 4 is a right view thereof.

FIG. 5 is a top view thereof.

FIG. 6 is a bottom view thereof.

FIG. 7 is a front right perspective view thereof; and,

FIG. 8 is a front left perspective view thereof.

The portions of the lidar shown in shown broken lines are for illustrative purposes and form no part of the claimed design. The broken lines consisting of dot-dash lines are boundary lines that show that the claimed design extends to the boundary line but does not include the boundary line.
